BAG CARRYING HANDLE

Allen I. Field, 147 Valley Stream Road, Larchmont, N.Y.
10538, and Sidney P. Field, 226 Beach 134th St., Belle Harbor, N.Y.

Filed July 30, 1970, Ser. No. 24,220

Term of patent 14 years

Int. Cl. D9—02

U.S. Cl. D9—292

FIG. 1 is a front elevational view of a bag carrying handle showing our new design;

FIG. 2 is a back elevational view thereof;

FIG. 3 is a top plan view thereof;

FIG. 4 is a bottom plan view thereof; and

FIG. 5 is a side elevational view thereof.

We claim:

The ornamental design for a bag carrying handle, substantially as shown.
